UNITED STATES PATENT OFFICE.

ARTHUR W. SMITH, OF ITHACA, NEW YORK.

STACK-SEAMING MANDREL.

1,170,355.

Specification of Letters Patent.

Patented Feb. 1, 1916.

Application filed April 19, 1915. Serial No. 22,353.

To all whom it may concern:

Be it known that I, ARTHUR W. SMITH, a citizen of the United States of America, residing at Ithaca, in the county of Tompkins 5 and State of New York, have invented certain new and useful Improvements in Stack-Seaming Mandrels, of which the following is a specification.

This invention relates to new and useful 10 improvements in stack seaming mandrels.

The primary object of the invention is to provide a mandrel upon which metal stack lengths may be firmly held and seamed by a single workman for either square or round 15 pipes and including elbows thus making it possible for a single man to perform the work which usually employs three or four men to complete.

A further object of the invention is the 20 provision of a stack forming mandrel adapted for making metal ventilating and heating stacks as well as stove pipes and partition pipes for furnaces and greatly reducing the expense of manufacturing the same.

A still further object is the provision of a 25 stack mandrel being formed adjustable for accommodating stack lengths of different dimensions and having a clamping device for holding the metal while the side seam of 30 the stack is being quickly double seamed upon the mandrel by a single workman employed in making the stack.

With these general objects in view and others that will appear as the nature of the 35 invention is better understood, the same consists in the novel combination and arrangement of parts hereinafter fully described, illustrated in the accompanying drawings and pointed out in the appended claims.

In the drawings forming a part of this 40 application and in which like designating characters refer to corresponding parts throughout the several views: Figure 1 is a side elevation of the device partially broken away and secured to a bench, a stack length 45 being illustrated as clamped upon the mandrel and shown in vertical longitudinal section. Fig. 2 is a top plan view thereof with parts broken away and the stack length 50 shown in horizontal longitudinal section. Fig. 3 is an elevational view of the clamp upon the work with the mandrel shown in transverse section and parts being broken away, and Fig. 4 is a sectional view of the 55 completed seam.

It will be understood that the stacks con-

templated by this invention such as furnace heating pipes are formed seamed in lengths up to eight feet long being formed of sheet metal such as galvanized iron which are 60 thereafter attached together in longitudinal alignment in the assembled stack formation. A mandrel is now designed whereby a single workman may rapidly complete the 65 formation of stack lengths, the device consisting essentially of the mandrel 10 of I-beam form removably and adjustably secured to a bench 11 or other stationary support by means of a collar bracket 12 attached to the bench by suitable bolts 13, the 70 mandrel being slidably mounted within the said bracket and retained in the desired adjusted position by means of opposite set bolts 14.

A form around which the metal is bent 75 into its stack form is provided upon the mandrel and the same is herein illustrated in connection with the forming of a stack length 15 which is rectangular in cross section. A desired number of pairs of position- 80 arms 16 are provided upon the mandrel and being slidably mounted through rectangular transverse openings 17 positioned centrally through the web 18 thereof, it being understood that the said arms are rec- 85 tangular in cross section and are provided with clamping positioning collars 19 slidably mounted upon the arms and adapted to be retained in the desired adjustment flatly engaging the opposite faces of the mandrel 90 web 18 by means of set screws 20 carried by the said collars. Arms 16 are preferably arranged in pairs, two pairs thereof being herein illustrated and have anvils 21 at their opposite outer ends. The sheet metal 15 95 being in the form of a strip before the same is bent into its stack formation is bent around the anvils 21 engaging the outer flat faces 22 thereof, while the stack length is formed of the desired dimensions by the 100 proper adjustment of the anvil arms 16.

It being understood that the adjacent longitudinal edges of the sheet metal are over-turned and positioned in interlocking engagement after the usual manner of forming 105 a seam, such interengaging portions are positioned flatly upon the outer face of one of the mandrel flanges 23, the seam portion being positioned directly over the central longitudinal groove 24 of such flange. A clamp 110 is arranged having a handle 25 to which an angular shank 26 is pivoted as at 27, while

spaced curved inclosing jaws 28 are provided upon the shank for slidably mounting the clamp upon the mandrel flange. The handle 25 has a terminal foot 29 for engaging the sheet metal and retaining the same in flat contact with the flange face when the said handle is shifted to a position substantially perpendicular to the mandrel. By this arrangement it will be seen that the sheet metal will be clamped to the mandrel when formed as a stack length and with its seam portion 30 in alinement with the adjacent groove 24 and whereupon the workman with the aid of the proper tools, such as a wooden mallet, may lightly pound upon the clamped metal thus forcing the seam portion thereof in place in the groove 24. The metal clamp is preferably positioned at a point upon the mandrel adjacent the free end thereof and the seam pounding operation is begun at the end of the length adjacent the bench and continues until the complete seam is formed within the mandrel groove 24, and the stack length or section is then complete and ready to be assembled. The free end of the mandrel is curved or rounded as at 31 for use in making elbow lengths or sections and it is to be understood that the mandrel 10 may be provided of any desired length.

From this detailed description of the invention, the manner of bending the sheet metal over the mandrel anvils in the form of a stack length will be at once apparent as well as the clamping of the metal upon the mandrel and the formation of the longitudinal locking seam therein by means of the mandrel groove 24 and whereby a single workman may readily and quickly form the desired size of stack length or unit.

While the form of the invention herein shown and described is what is believed to be the preferred embodiment thereof, it is nevertheless to be understood that minor changes may be made in the form, proportion and details of construction without departing from the spirit and scope of the invention as set forth in the appended claims.

What is claimed as new is:—

50 1. A stack forming device comprising an adjustably mounted mandrel of I-beam form having central longitudinal seam forming grooves upon the outer faces of the base flanges thereof, and adjustably mounted anvils carried by the mandrel web.

2. A stack forming device comprising an adjustably mounted mandrel of I-beam form

having central longitudinal seam forming grooves upon the outer faces of the base flanges thereof, longitudinally shiftable parallel arms transversely carried by the web of the said mandrel, flat faced forming anvils upon the opposite outer ends of the said arms.

3. A stack forming device comprising an 65 adjustably mounted mandrel of I-beam form having central longitudinal seam forming grooves upon the outer faces of the base flanges thereof, longitudinally shiftable parallel arms transversely carried by the web 70 of the said mandrel, flat faced forming anvils upon the opposite outer ends of the said arms, the outer end of the said mandrel being rounded and a sheet metal clamp slidably mounted upon one of the base flanges 75 of the mandrel.

4. A stack forming device comprising a rigidly mounted collar bracket, a mandrel bar I-shaped in cross section slidably mounted within the said bracket, adjusting screws 80 for said mandrel carried by the bracket, the said mandrel having the free end thereof rounded and its opposite base flanges provided with central longitudinal seam forming grooves.

5. A stack forming device comprising a rigidly mounted collar bracket, a mandrel bar I-shaped in cross section slidably mounted within the said bracket, adjusting screws 90 for said mandrel carried by the bracket, the said mandrel having the free end thereof rounded and its opposite base flanges provided with central longitudinal seam forming grooves, and the web of said mandrel having rectangular perforations 95 there-through, arms arranged in pairs within the said perforations and being formed rectangular in cross section, positioning collars adjustably mounted upon said arms at opposite sides of the mandrel web, forming anvils upon the outer ends of the said arms having outer flat engaging faces.

6. A device of the class described comprising a mandrel, adjustable anvil forms carried thereby and adapted for receiving sheet metal bent thereover encircling the mandrel, the said mandrel being provided with opposite longitudinal seam forming grooves adapted for the forcible reception of the interlocked free edges of the sheet metal and sheet metal clamping means carried by the mandrel.

In testimony whereof I affix my signature.
ARTHUR W. SMITH.
